Primary Examiner — Paula Allen Greene*(74) Attorney, Agent, or Firm* — Raven Patents, LLC;
Anton E. Skaugset(57) **CLAIM**

The ornamental design for headphones, as shown and described.

DESCRIPTION

FIG. 1 is an upper, front, and left side view of headphones showing the new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a lower, rear, and left side view thereof; and,

FIG. 9 is a lower, rear, and left side view thereof, illustrating the headphones coupled to a headphone cable.

Features shown in broken lines form no part of the claimed design.

1 Claim, 8 Drawing Sheets(56)
